UNITED STATES PATENT OFFICE.

CLINTON O. HARRINGTON, OF SWISSVALE, PENNSYLVANIA, ASSIGNOR TO THE UNION
SWITCH & SIGNAL COMPANY, OF SWISSVALE, PENNSYLVANIA, A CORPORATION OF
PENNSYLVANIA.

RAILWAY-SIGNAL.

1,298,938.

Specification of Letters Patent.

Patented Apr. 1, 1919.

Application filed September 14, 1918. Serial No. 254,102.

To all whom it may concern:

Be it known that I, CLINTON O. HARRINGTON, a citizen of the United States, residing at Swissvale, in the county of Allegheny and 5 State of Pennsylvania, have invented certain new and useful Improvements in Railway-Signals, of which the following is a specification.

My invention relates to railway signals; 10 and particularly to signals of the type comprising a semaphore biased to the "stop" position, a motor for moving the semaphore to one or more "proceed" positions, and means including an electromagnet for holding the semaphore in the position or positions to which it has thus been moved. In 15 the form of signal which I shall describe, the means including the electromagnet is also employed to operatively connect the motor 20 with the semaphore to enable the former to move the latter.

In signals of this character, the load on the electromagnet is not as great when the semaphore is being held at rest in the proceed position or positions, as it may be at other times particularly when the semaphore is moving from one position to another. It follows, therefore, that the degree of energization of the magnet may be less while the 30 semaphore is being held in the proceed position or positions than at other times, with the result that the total energy consumed by the signal is greatly reduced, because, under usual conditions, the total time per day that 35 a signal is held in the "proceed" position is much greater than the time it occupies other positions, and likewise much greater than the time consumed in moving from one position to another by motor energy.

40 One object of my invention, then, is the provision of means for so changing the connections of the individual coils of the said electromagnet with the source of current that such coils receive a high degree of energization at such times as they may be called upon to exert maximum pull, and a lesser degree of energization at other times in order to economize in power consumption. In the 45 form of my invention shown herein, this is 50 accomplished by connecting the two coils of the magnet in multiple to secure the high degree of energization, and in series to secure the lesser degree of energization.

I will describe one form of signal embody-

ing my invention, and will then point out the 55 novel features thereof in claims.

In the accompanying drawings, Figure 1 is a view showing in front elevation, partly diagrammatic, one form of signal embodying my invention. Fig. 2 is a view showing 60 in side elevation part of the signal shown in Fig. 1. Fig. 3 is a diagrammatic view showing one arrangement of circuits, also embodying my invention, for the control of the signal shown in the preceding views. 65

Similar reference characters refer to similar parts in each of the views.

Referring first to Figs. 1 and 2, the reference character S designates a semaphore which is pivotally mounted on a supporting 70 mast or post 33. This semaphore is biased to the "stop" or horizontal position as shown in solid lines, but may be moved to a "caution" or inclined position, and to a "proceed" or vertical position, as indicated in dash lines, 75 by means of an electric motor M through the medium of suitable operating mechanism. In order to simplify the explanation of the operation of certain circuit controllers embodied in the signal, it is understood that, 80 for the purpose of the present specification, the caution position of the semaphore is its "45° position," and the proceed position of the semaphore is its "90° position."

The operating mechanism for moving the 85 semaphore S comprises an arm 34 pivotally mounted at point 34^a and operatively connected with the semaphore S through suitable means indicated by the dot and dash line 46. The arm 34 is moved by chains 37 90 and 37^a, which chains are in turn driven by the motor M in the direction indicated by the arrows in Fig. 1. The chain 37 operates over a sprocket wheel 43 and another sprocket wheel 44, the first of these wheels 95 being driven by the motor through suitable reduction gearing which is not shown in the drawing but which is included in the connection indicated by the dash line 65. The chain 37^a operates over a sprocket wheel 45 100 and another sprocket wheel 47, which latter is mounted directly behind the wheel 44 and is attached to the same shaft 48 as the latter wheel. The chain 37 is provided with rollers 38, and chain 37^a is similarly provided with 105 rollers 38^a, which rollers project laterally from the chains to engage with a fork 35 pivoted at point 35^a in arm 34. Two pairs of

rollers are provided for each chain, and the two pairs are disposed at opposite points on the chain. The fork 35 comprises three parallel prongs (only one of which is shown), the first and second of which coact with the rollers 38 on chain 37 and the second and third of which coact with the rollers 38^a on chain 37^a.

The fork 35 is controlled by an electro-
10 magnet D through a toggle mechanism 36 in the arm 34, the control being such that when the magnet is energized the fork is held rigidly in the position shown with respect to arm 34, that is, in a projected position

15 in the path of rollers 38 and 38^a, but that the fork is free to swing upwardly to a retracted position out of the path of these rollers when the magnet is deenergized. It follows, then, that when magnet D is en-

20 ergized, and motor M drives the chain 37, one pair of rollers 38 on this chain will engage the fork 35 and so elevate arm 34 and semaphore S to the intermediate or caution position, in which position the rollers pass

25 out from under the fork and the fork is caught and held by hook 41^a on a latch 41. This latch is pivoted to the frame work of the signal mechanism at 41^c, and is biased to the position in which it is shown by a spring

30 42. If now the motor M is again operated, the fork 35 will be caught by one of the pairs of rollers 38^a on chain 37^a, so that the arm 34 and semaphore S will be elevated to the highest or proceed position, where the

35 rollers will pass out from under the fork and the fork will be caught and held by hook 41^b on latch 41. The semaphore will then remain in this position until magnet D becomes deenergized, whereupon the fork 35

40 will swing upwardly with respect to arm 34 and so become disengaged from latch 41, so that the arm 34 and semaphore S will drop to their lowest positions, as shown in the drawing.

45 The reference character C designates a circuit controller which is normally closed, but which is opened by a knob 40 of insulating material on arm 34 just before this arm reaches its highest position. The function of this circuit controller will appear hereinafter.

Attached to the frame work of the operating mechanism is another circuit controller A which is controlled jointly by the latch 41 and the rollers 38^a on chain 37^a, through the medium of apparatus which I will now describe.

The latch 41, as has been said, is pivoted in the framework of the mechanism at 41^c.
60 This pivotal connection is such, however, that the latch is capable of a slight amount of movement in a general vertical direction, and this is accomplished as follows. The latch comprises two vertically disposed arms (see Fig. 2) which are attached to a sleeve

16, and this sleeve in turn swings freely on the pivot pin 41^c. The pivot pin passes through holes 17 in the framework of the mechanism (see Fig. 2), which holes are slightly elongated in a vertical direction, thus 70 providing for the desired vertical movement of the latch. The swinging movement of latch 41 on its pivot pin 41^c permits the fork 35 to move the latch out of its path as the arm 34 approaches the intermediate and 75 highest positions. The angle through which the latch can swing is preferably limited, however, by a pin 20 which is fixed in the framework of the mechanism and which passes through a slot 21 in each arm of the 80 latch as shown in Fig. 1.

18 is a bell crank lever which is mounted to swing on a pin 19 suitably supported in the framework of the mechanism. One arm of this lever projects under the pivot pin 41^c 85 and engages therewith, the sleeve 16 being cut away as shown in Fig. 1 to permit the lever arm to engage directly with the pivot pin. Inasmuch as the lever arm engages the pin and not the sleeve, the friction between 90 the arm and the pin has no tendency to interfere with the swinging of the latch 41 on its pivot pin. The other arm of the lever 18 projects downwardly and is connected with the lower arm of a second lever 22 through the medium of an adjustable link 23. Lever 22 is fixed to a shaft 24 which is journaled in a yoke 25 attached to the framework of the mechanism. This lever 22 is biased by a torsion spring 26 (see Fig. 2) to swing in 95 100 105 110 115 120 125 130 135 140 145 150 155 160 165 170 175 180 185 190 195 198 clockwise direction as viewed in Fig. 1, and hence this lever exerts a force on lever 18 tending to turn the latter in the same direction. When the latch 41 is not engaged by fork 35, this tendency of lever 18 to swing 105 raises the latch to its highest position, but when the fork rests on either hook of the latch, the weight of arm 34 of semaphore S overcomes the action of spring 26 and so moves the latch down and causes levers 18 110 115 120 125 130 135 140 145 150 155 160 165 170 175 180 185 190 195 198 and 22 to swing in clockwise direction from the positions in which they are shown in Fig. 1.

Attached to the upper arm of lever 22 is a block 27 of insulating material which actuates the movable contact fingers of circuit controller A. When the parts are in the positions shown in Fig. 1, contacts 2-3 and 4-5 are closed, but when lever 22 is swung by the weight of arm 34, etc., on latch 41, 120 these two contacts become opened and contact 3-5 becomes closed. As shown in Fig. 3, a second contact operating arm 22^a is attached to the shaft 24 to actuate a contact 6-7, but this contact and its actuating arm 125 are omitted from Figs. 1 and 2 to simplify the drawing.

In the present form of my invention, the shaft 24 is provided with an upwardly projecting cam 28 which is arranged to coact 130

with rollers 38^a. If a pair of rollers engages this cam 28 while the latch 41 is depressed by arm 34, the rollers will push the cam outwardly, and so will elevate latch 41 and reverse the contacts of circuit controller A. The reason for this actuation of circuit controller A will appear hereinafter.

The arm 34 controls two other circuit controllers which are illustrated in Fig. 3, but are omitted from Fig. 1 to simplify the drawing. Referring to Fig. 3, a shaft 29 is operatively connected with arm 34, and fixed to this shaft is a cam 30 which controls a contact finger 32 in the manner indicated by the legends on the drawing. Also attached to shaft 29 is a contact segment 31 which coacts with contact fingers 14 and 13. In order that contact 14-31 may change at different positions of the semaphore according as the latter is moving up or down, segment 31 is provided with a drag segment 31^a which is freely mounted on shaft 29 but is constrained to a limited movement with respect to segment 31 by a pin and slot connection or by suitable equivalent means. This drag segment causes contact 14-31 to operate in the manner indicated by the legend on the drawing.

Operating current is supplied to the motor 30 M and electromagnet D from a battery B, (see Fig. 3). The supply of current from this battery to the signal is controlled by suitable means such as a polarized relay R, which relay comprises neutral armature contacts 8 and 9, and a polarized armature contact 10. The relay R is supplied with current from a battery 15 and is controlled by a pole-changer P in the usual and well known manner.

40 The operation of the signal and of the controlling circuits is as follows:

When the relay R is deenergized, the motor M, and magnet D are deenergized, so that the semaphore S is in the stop position and all of the other parts of the signal are in positions in which they are shown in Figs. 1 and 3. I will now assume that pole-changer P is operated to energize relay R in such direction that the polarized armature contact 10 remains open. The closing of the neutral armature contacts of this relay causes magnet D to become energized, the circuit being from the upper terminal of battery B, through wire 12, front contact 8 of relay R, wire 49, wire 50, contact 51-32, wire 52, wire 53, coil d' of magnet D, wire 54, contact 3-2, wires 55 and 56, contact 9 of relay R, and wire 57 to battery B. Coil d' of magnet D is in multiple with the circuit for coil d', the connection being from wire 52, through wire 58, contact 4-5, wire 59, coil d² and wire 60 to wire 56. It will be noted that at such time the coils of magnet D are connected in multiple with the source of current, so that the energization

of this magnet is comparatively high. The circuit for motor M is from the upper terminal of battery B, through wire 12, contact 8, wires 49 and 61, contact 14-31, wire 62, contact 7-6, wire 63, motor M and wire 64 to the lower terminal of battery B. Motor M and magnet D both being energized, the arm 34 is then raised by the rollers on chain 37 so that the semaphore S is moved to its intermediate, or caution, or 45° position. Just as this position is reached, the rollers 38 pass from under fork 35, and this fork is deposited on the hook 41^a of latch 41. The consequent downward movement of this latch causes the reversal of circuit controller A, and the opening of contact 6-7 in this circuit controller opens the circuit for motor M, whereupon the motor stops and the chains come to rest. The reversal of circuit controller A also shifts the connections for the coils of magnet D, so that these coils are then connected in series, the circuit being from battery B, through wire 12, contact 8, wires 49 and 50, contact 51-32, wires 52 and 53, coil d', wire 54, contact 3-5, wire 59, coil d², wires 60 and 56, contact 9, and wire 57 to battery B. The consequent lower degree of energization of magnet D is sufficient to enable this magnet to hold the fork 35 in engagement with latch 41.

I will now assume that when the semaphore is in the caution or intermediate position, pole-changer P is reversed, so that relay R becomes energized in such direction as to close its polarized armature contact 10. A new circuit for motor M is then closed, as follows: from battery B, through wire 12, contacts 8 and 10 of relay R, wires 66 and 69, contact C, wires 70 and 63, motor M and wire 64 to battery B. Motor M, therefore, operates to move the chains 37 and 37^a in the direction indicated by the arrow in Fig. 1. Just before the rollers 38^a which are at the bottom of chain 37^a raise fork 35 from hook 41^a, the rollers adjacent the top of this chain engage with cam 28 to swing shaft 24 in counter-clockwise direction, thereby reversing circuit controller A and raising latch 41 in a vertical direction. This operation of circuit controller A returns the contacts to the positions in which they are shown in Figs. 1 and 3, so that the coils of magnet D are again connected in multiple. As soon as the fork 35 has been lifted from the latch 41, the force opposing the action of spring 26 is, of course, removed so that circuit controller A remains in the position shown in Fig. 3, even though the rollers 38^a pass away from cam 28. When the semaphore reaches the 55° position, cam 30 reverses the position of contact finger 32, so that the circuit hereinbefore traced for magnet D becomes opened and this magnet becomes energized through the following circuit: from battery B, through wire 12, contacts 8 and 10, wire 66, 130

wire 67, contact 68—32, and thence as before through the coils d' and d^2 in multiple, to the lower terminal of battery B. Just before the semaphore reaches the proceed or 90° position, contact C is opened by the knob 40 on arm 34, but prior to this operation the contact finger 13 has been engaged by contact segment 31, so that a branch for the motor circuit has been closed around contact 10 C, which branch is from wire 66, through contact 13—31, wire 62, and contact 7—6 to wire 63. The motor continues to operate, therefore, until the rollers 38^a have passed out from under fork 35 and the fork has been 15 deposited on the hook 41^b of latch 41. When this happens, the downward movement of the latch 41 reverses circuit controller A as before, so that the motor circuit is opened at contacts 6—7 and the coils of magnet D are 20 again placed in series. The consequent lower energization of magnet D is, however, sufficient to cause this magnet to hold the fork 35 in engagement with the latch 41.

It follows from the foregoing that while 25 the signal is being held in the caution or the proceed position, magnet D consumes less energy than at other times while this magnet is functioning, and so the total amount of energy required for the operation of the 30 signal is materially reduced.

If, while the signal is in the proceed position, pole-changer P is returned to its intermediate position, relay R will become de-energized so that the circuit for magnet D 35 will be opened, whereupon arm 34 and semaphore S will drop to the positions in which they are shown in Fig. 1 and the signal will then again indicate stop. If, however, while the signal is in the proceed position, pole- 40 changer P is reversed so that relay R becomes energized in such direction that its polarized contact 10 opens, magnet D will at first be deenergized, so that the semaphore will start to move toward the stop position.

45 When, however, the semaphore reaches the 55° position, contact finger 32 will reverse, so that the magnet D will become energized with its two coils connected in multiple. Fork 35 will then be caught and held by 50 hook 41^a on latch 41, so that the semaphore will stop in the caution or 45° position. During this last movement contact 14—31 does not close, because of the action of the drag segment 31^a.

55 Although I have herein shown and described only one form of signal embodying my invention, it is understood that various changes and modifications may be made therein within the scope of the appended 60 claims without departing from the spirit and scope of my invention.

Having thus described my invention, what I claim is:

1. A signal comprising a semaphore biased 65 to one position, means for moving it to one

or more other positions, mechanism for operatively connecting said semaphore and said means and for holding said semaphore in the position or positions to which it has been moved by said means, said mechanism including a magnet having two coils, and means for connecting said two coils in series when the semaphore is at rest in the position or one of the positions to which it has been moved by said moving means, and for connecting the coils in multiple at other times.

2. A signal comprising a semaphore biased to one position of indication, means for moving it to another indicating position in opposition to the biasing force, a latch for holding the semaphore in the latter position, mechanism including a magnet having two coils for operatively connecting the semaphore with said moving means and with said latch, and contacts and conductors for connecting said two coils in series while the semaphore is being held by said latch and in multiple at other times.

3. A signal comprising a semaphore biased to one position of indication, means for moving it to another indicating position in opposition to the biasing force, a latch for holding the semaphore in the latter position, mechanism including a magnet having two coils for operatively connecting the semaphore with said moving means and with said latch, and means controlled by said latch for connecting said coils in series while the semaphore is being held by said latch and in multiple at other times.

4. A signal comprising a semaphore biased to one position of indication, means for moving it to another indicating position, mechanism for holding the semaphore in the latter position comprising a latch mounted on the framework of the signal, a fork operatively connected with the semaphore for movement with relation to the semaphore, a magnet having two coils for holding said fork in engagement with said latch, said latch being mounted for slight movement by the fork and biased in the opposite direction, and a circuit controller operated by said latch for connecting said coils in series when the fork is being held by the latch and in multiple at other times.

5. A signal comprising a semaphore biased to one indicating position, means for moving it to two other indicating positions in opposition to the biasing force, mechanism for holding the semaphore in each of the latter positions and including a magnet having two coils, and contacts and conductors for connecting said coils in multiple while the semaphore is moving from one of the two latter indicating positions to the other in response to the biasing force and for connecting said coils in series after the semaphore has been brought to rest in the last mentioned position.

6. A signal comprising a semaphore biased to one indicating position, means for moving it to an intermediate and an extreme indicating position in opposition to the biasing force, mechanism for holding the semaphore in each of the two latter positions and including a magnet having two coils, and means for connecting said coils in multiple while the semaphore is moving from said 10 extreme position to said intermediate position in response to its bias, and in series after said semaphore has been brought to rest at said intermediate position.

7. A signal comprising a semaphore biased to stop position, a motor for moving it to a proceed position, means including an electromagnet having two coils for operatively connecting said semaphore with said motor and for holding the semaphore in the said 20 proceed position, and means for connecting said two coils in series or in multiple according to the load on said electromagnet.

8. A signal comprising a semaphore biased to stop position, means for moving said 25 semaphore to caution and proceed positions, a latch for holding the semaphore in caution and proceed positions, mechanism including an electromagnet having two coils for connecting said semaphore with said moving 30 means and with said latch, means controlled by said latch for connecting said two coils in series while the semaphore is being held by the latch and in multiple at other times, and

means controlled by said moving means for connecting said two coils in multiples when the semaphore is held in the caution position by said latch and the moving means is about to move the semaphore toward the proceed 35 position.

9. A signal comprising a semaphore biased to stop position, means for moving said semaphore to a caution and a proceed position, a latch capable of slight movement by the weight of the semaphore for holding the semaphore in the caution and proceed positions, mechanism including an electromagnet having two coils for connecting said semaphore with the moving means and with said latch, a circuit controller operated by the movement of said latch for connecting said 40 two coils in series while the semaphore is being held by the latch and in multiple at other times, and means controlled by said moving means for reversing said circuit controller in opposition to the action of the semaphore thereon when the semaphore is being held in the caution position and the moving means starts in operation to move the semaphore toward the proceed position.

In testimony whereof I affix my signature 50 in presence of two witnesses.

CLINTON O. HARRINGTON.
